UNITED STATES PATENT OFFICE.

FRIEND W. SMITH, OF BRIDGEPORT, CONNECTICUT, ASSIGNOR TO THE NATIONAL LOCK WASHER COMPANY, OF NEWARK, NEW JERSEY, A CORPORATION OF NEW JERSEY.

SASH HOLDER.

Application filed July 14, 1925. Serial No. 43,472.

This invention relates to sash holders such as are used on railroad car windows, but has especial reference to that class of such devices in which the operation of the lever to 5 elevate the sash, also causes a vertically disposed plunger to be driven directly against the window sill for the purpose of releasing the sash when it adheres to such sill as by sticking. Heretofore devices of this de- 10 scription have been employed in which the sash was released by the action of a cam carried by the lifting lever and operating directly against a vertically disposed plunger and the especial object of the present inven- 15 tion is to develop a construction of this sort on lines somewhat different.

In the accompanying drawing which forms a part of this application—

Figure 1 is a broken and partly sectioned 20 elevation showing the improvement installed on a window sash with a locking engagement effected with the metal rack at the side of the window frame.

Figure 2 is a similar view showing the 25 position of the various parts when the lever has been raised to drive the plunger against the sill and release the sash.

Figure 3 is a rear elevation of the sash holder and with the window casing sectioned 30 and showing the parts in the same position as in Figure 1, and

Figure 4 is a detail perspective of the lifting lever.

Similar numerals of reference denote like 35 parts in the several figures of the drawing.

1 is the casing of the sash holder preferably secured to the sash A by means of pins 2 driven through bosses 3 in the usual manner.

40 4 is the plunger pin which is vertically disposed and supported within the casing by the front edge 5 thereof and by the outer wall 6, the lower end of said plunger being contained and guided within a housing 7 which projects from the bottom of the cas- 45 ing.

8 represents a metal rack such as is usually secured to the side of the window casing and with which the locking member ordi- 50 narily engages as will be presently seen, and the bottom of this rack is preferably ex- tended so as to form a foot 9 upon which the bottom of the housing rests when the

sash is closed. This foot affords a striker for the plunger pin, and avoids the necessity of providing a special striker mortised 55 in the window sill.

The sash lever is denoted by the numeral 10 and is formed at its inner portion with an enlargement 11 which is pivoted around 60 a hollow post 12 that is cast with the casing, a screw 13 being driven within the post outside the enlargement 11 so as to retain the operating lever in position.

The plunger 4 is provided on its face ad- 65 jacent the enlargement 11 with rack teeth 14, and the enlargement 11 at one portion thereof is circular and provided with gear teeth 15 which are in mesh with the teeth 14, so that it will be clear that when the lever 70 10 is elevated the plunger will be driven downwardly.

Extending from the enlargement 11 in the rear of the toothed portion is the ordinary lock dog 16 which is normally project- 75 ed into locking engagement with the side rack 8 by a spring 17 whose ends bear against the lock casing and the heel end of the dog 16 in the usual manner.

The parts are shown in their normal po- 80 sition at Figure 1 and it will be observed that the bottom of the plunger 4 is slightly above the foot 9, so that when the lever is elevated, the locking dog will have been released from the side rack by the time the 85 plunger has come in contact with this foot 9, so that there can be no interference in the elevation of the sash by the impact of the plunger against said foot as will be noted in Figure 2 where such elevation has been 90 effected.

After the sash has been released by the operation of the lever 10 in the manner be- 95 fore described, it may be elevated in the usual manner by lifting upward on the lever, it being, of course, understood that there are two of these constructions one at the bot- 100 tom of each side of the sash. After the sash has been elevated sufficiently the lever 10 is released, and the spring 17 will there- upon force the dog toward the rack so that 105 it will rest on one of the teeth thereof in the usual manner, and this action of the spring will restore the lever 10 to its nor- mal or lowered position and will thus cause the plunger 4 to be elevated to the position

shown at Figure 1, so that it cannot project below the bottom of the sash and present an unsightly appearance.

The casing has extending therefrom the usual stationary lever 18 which is utilized by the operator in getting a purchase so as to exert great lifting power on the lever 10.

What is claimed is:—

A combined sash holder and window release comprising a casing having a pivotal post, a sash holder lever having a hub intermediate its ends pivoted on said post said hub having teeth on its periphery and said

lever having its inner end extending forwardly from the hub to form a sash holder and having its outer end projecting outwardly from the casing and a vertically disposed plunger in the casing having rack teeth in mesh with the teeth of the hub whereby both the upward and downward movements of the lever will effect positive movement of the plunger into and out of operative position respectively.

In testimony whereof I affix my signature hereto.

FRIEND W. SMITH.
